CULVERT FORMING MACHINE

Meril L. Eckman, North West Canton, Ohio, assignor to Republic Steel Corporation, Cleveland, Ohio, a corporation of New Jersey

Application January 30, 1947, Serial No. 725,362

8 Claims. (Cl. 153—39)

1

This invention relates to an apparatus for deforming sheet metal bodies and more particularly to an apparatus for converting cylindrical culvert blanks into culvert sections having flattened bottoms and arched tops.

The object of the present invention is to provide means whereby a substantial length of corrugated pipe may be deformed in one operation.

A further object of the invention is to eliminate or reduce slippage, during the deforming operation, between the culvert and the flattening means.

A further object is to eliminate or reduce undue stresses in the corrugated sheet metal culvert during the deforming operation.

Other objects and advantages will become apparent from the following description of a machine embodying the invention.

In general the apparatus of the invention comprises a die having a recess corresponding to the desired arched top of the finished culvert, a plurality of platens positioned above the recess and a means for simultaneously actuating the platens to apply sufficient pressure to the cylindrical culvert blank to shape said blank into conformity with the recess of the die and flatten the portions of the culvert blank engaged by the platens.

In a particularly satisfactory embodiment of the invention, two platens are provided, which are slidably mounted on rods hinged at points along two sides of the recessed die. The free edges of the platens are adjacent and directly above the recess, for example on lines parallel with the axis of the culvert blank. The platens are actuated by a reciprocating ramming member connected to a frame having crossheads which are pivotally connected, directly to both platens, the frame having longitudinal beam heads between said crossheads. Reciprocation of the ramming member in one direction causes the platens to move toward the recess and causes the angle, made by the faces of the platens to flatten. The cylindrical culvert blank, which is positioned in the recess, is pressed into conformity with the configuration of the recessed die and that portion of the blank which is in contact with the platens becomes flattened. The free ends of the platens maintain substantially the same spatial relationship to each other by sliding outwardly on the hinged rods as the platens move downwardly in the deforming operation. Reciprocation of the ramming member in the other or upward direction causes the free ends of platens to draw upward away from the recess to permit removal of

2

the deformed culvert and insertion of a cylindrical culvert blank for another cycle.

For a more complete description of the apparatus and its operation I refer now to the drawings, which show an example of one form of construction, and in which:

Figs. 1 and 2 are end elevations of the apparatus, Fig. 1 showing the platens in the raised position, Fig. 2 showing the platens in the closed position.

Fig. 3 is an enlarged sectional end view of one of the platens taken along the line 3—3 of Fig. 4.

Fig. 4 is a horizontal section view of the apparatus taken along the line 4—4 of Fig. 2.

Fig. 5 is a view of the fulcrum block hinge for the hinged rods, taken along the line 5—5 in Fig. 3.

Fig. 6 is a side elevation of the apparatus.

Fig. 7 is a fragmentary perspective view of one of the removable dies.

The apparatus comprises a frame 10, which supports a stationary die 11, with nested removable dies 12, the recess of each die corresponding to the desired finished size of the top of an arch type culvert. Two platens 13 are positioned above the dies and are supported at their sides on the rods 14 which make a sliding fit with the tubes 15 welded to the platens 13 (as best shown in Fig. 3). The rods 14 are hinged to the frame 10 at the fulcrum block hinges 19. The platens 13 are connected to vertically reciprocating, hydraulic or mechanical rams 16 by means of a slidably mounted frame comprising crossheads 17, to which the platens 13 are pivotally connected at the crosshead hinges 18, and longitudinal beam heads 33. Each crosshead, arranged to slide up and down in the frame 10, is thus adapted to transmit pressure to both platens at appropriate localities on their top surfaces, and the positional relationship of each crosshead hinge axis to the inner edge 22 of the bottom face of the platen is conveniently such that these adjacent inner edges have practically no lateral movement as the crossheads move down in operation. As shown in the side elevation, Fig. 6, the platens 13 have a substantial longitudinal extent to permit the deforming of a length of culvert section in one operation. The rams 16 and crossheads 17 are spaced at intervals along the length of the platens and said crossheads are connected by longitudinal beam heads 33. Where a plurality of rams are used (e. g. two, as shown) the hydraulic type is especially useful in affording good equalization and other coordination during the downward stroke.

In operation the removable dies 12 are nested within the stationary die 11 until the die of the desired size is in position. A cylindrical culvert blank 20 is placed in the recess 21 (as shown in Fig. 1) of the top die 12. The reciprocating rams 16 are actuated and move downward toward the blank 20. The rams 16 in turn actuate the platens 13 through the crossheads 17 and crosshead hinges 18. As the free edges 22 of the platens 13 are pressed downward the angle made by the flat surfaces 23 of the platens 13 flattens out and the outer edges 24 of the platens 13 slide along the hinged rods 14 toward the fulcrum block hinges 19. The pressure exerted by platens 13 upon the culvert blank 20 forces that portion of the blank which is in the top die 12 to conform to the shape of the recess 21 and that portion of the blank which is engaged by the platens to flatten. When the downward movement of the reciprocating rams 16 is completed the flat faces 23 of platens 13 are substantially horizontal and lie in the same plane and in substantially continuous contact with the flattened surface of the deformed culvert 30 as shown in Fig. 2. The rams 16 are then actuated to move upward. The free edges 22 of platens 13 are drawn up by the operations of the rams 16 through the crossheads 17 and crosshead hinges 18. The platens 13 pivot at the crosshead hinges during the upstroke, and the flat faces 23 of the platens move out of the horizontal plane and form an angle between them. The outer edges 24 of platens slide along the hinged rods 14 away from the fulcrum hinges 19 and the rods 14 pivot upward as the platens 13 are retracted. When the rams 16 have completed their upward movement the culvert 30 which has been deformed in the manner described may be removed from the recess 21 and another cylindrical culvert blank placed in position for the next cycle.

It has been found that the use of two or more platens in exerting pressure on the culvert blank is preferable to a single reciprocating die. The pivoting and sliding motion of the platens 13 toward the fulcrum hinges 19 urges the metal toward the small corners 32 of the culvert 30 during the forming operation and results in easier and more accurate forming of the culvert. Furthermore, there is substantially no slippage between the platen faces and the culvert.

The apparatus of my invention may be adjusted to shape culverts of various diameters by increasing or decreasing the size of the removable or temporary dies 12, e. g. by inserting a greater or less number of the latter in nested relation. I have found that satisfactory temporary dies may be constructed with steel boiler plate for the contour of the recess and wooden spacer blocks 25 to give the desired diameter and give support to the die under pressure. The spacer blocks 25 are held in position on the outside of the die by countersunk screws 26 (see Fig. 7). In adjusting the apparatus to shape culverts of different diameters vertical adjustment of the fulcrum block hinges 19 is necessary. For this purpose additional holes 27 have been provided along the vertically disposed angle members 28 carrying the fulcrum block hinges 19 (as shown in Fig. 3). The fulcrum block hinges 19 may be adjusted by removing the nuts 29 and bolts 31 (see Fig. 5) and replacing them when the hinges have been moved vertically to the desired position. The stroke of the rams 16 may also be vertically adjusted during operation, i. e. either lengthened or shortened as the case may be so that the platens

13 will lie in the desired relation, preferably a horizontal plane, at the end of the downward pressure stroke.

It has been found that the working surfaces 5 of both the platens and the recessed dies may be smooth, as shown, and yet produce an appropriately corrugated culvert from blanks of culvert pipe corrugated in the usual manner. The illustrated machine will accommodate blanks of various sizes; in forming culverts which are longer than the length of the platens, one particularly effective procedure involves inserting one end of the blank in the machine and partially deforming it, then repeating the operation as the pipe 10 is progressively moved through the press, until the full length has been partially deformed, and finally putting the blank progressively through the press a second time to complete the forming 15 operation.

20 In the specification I have described only one form of my invention, however it will be apparent that various modifications may be made within the scope of the invention and it is not desired to limit my invention except as indicated in the 25 appended claims.

I claim:

1. In an apparatus for converting a cylindrical sheet metal culvert blank into a culvert having a flat bottom and an arched top, a die constructed to provide a recess for receiving the blank and having the configuration of the desired arch, a pair of platens having substantially flat faces for engaging the sheet metal blank, means mounting the platens to rock upon the 30 surface of the culvert blank about axes respectively adjacent the sides of the die, and means for actuating the platens to flatten the portions of the blank engaged by said faces and shape the rest of the blank against the wall of the recess in 35 the die, said actuating means including means for rocking the platens about the aforesaid axes toward the blank so that said actuating means causes the platens to exert deforming pressure on the blank at localities progressively nearer 40 the center thereof.

2. In an apparatus for forming an arch type sheet metal culvert from a cylindrical sheet metal blank, a die having a longitudinal recess to receive said cylindrical blank, said recess conforming in shape and dimensions to the desired arch, a pair of platens having substantially flat lower faces for engaging the blank, hinge means for the platens disposed at the sides of the die, for supporting the platens to swing about axes adjacent 50 said sides, with the inner edges of the platens thereby movable toward and away from the die in the vicinity of a central region thereof, and means for swinging the platens on their hinges to move their inner edges toward the die and thereby to flatten the portions of the blank engaged by 55 said faces and shape the rest of the blank to conform to the interior of the recess in the aforesaid die.

3. In an apparatus for forming arch-type sheet 65 metal culverts from substantially cylindrical sheet metal blanks, a lower platen constructed to provide a longitudinal recess, to receive said blanks, said recess conforming substantially to the shape and dimensions of the desired arch, supporting structure at the sides of the lower platen, a pair of platens hinged at their outer edges to said supporting structure and having their inner, free edges above said recess, the work engaging faces of said platens being substantially flat, and means movable relative to said

structure, for simultaneously actuating said platens to swing their inner edges toward the lower platen and thereby to flatten the portions of blanks engaged by them and conform other portions of the blank to the interior of the recess in the die.

4. In an apparatus for converting a cylindrical sheet metal culvert blank into a culvert having a flat bottom and an arched top, a die constructed to provide a recess for receiving the blank and having the internal configuration of the desired arch, supporting structure, a pair of hinged rods, said rods being hinged on said supporting structure to swing about predetermined localities at the sides of the die, a pair of platens slidable on said rods and having substantially flat faces for engaging the blank, and actuating means comprising a reciprocating hydraulic ram connected to both platens for simultaneously sliding the platens on the hinged rods and swinging the rods on their hinges and thereby forcing the flat faces of the platens into engagement with portions of the blank with sufficient pressure to flatten said portions and shape the rest of the blank against the interior of the recess in the die.

5. In an apparatus for converting substantially cylindrical shells into culverts of the flat bottom arched-top-type, a supporting frame work comprising vertical side members, a plurality of rods each hinged at one end on said members, a pair of platens slidably mounted on said rods and having substantially flat lower faces, a die below said platens having a longitudinal recess for receiving the cylindrical shells and corresponding in shape and dimensions to a desired arched culvert top, and platen actuating means comprising a reciprocative member pivoted directly to both of the platens, reciprocation of said member in one direction sliding the platens outward on the aforesaid rods as the platens apply deforming pressure to shells held in the recess of the die.

6. In an apparatus for converting substantially cylindrical shells of varying diameters into culverts having substantially flat bottoms and arched tops, a supporting framework comprising vertical side members, a plurality of rods each hinged at one end on said members, a pair of platens slidable on said rods and having substantially flat lower faces, a set of nested dies each having a recess corresponding in shape and dimensions to a desired arch, said dies being relatively movable to expose an appropriate cylindrical shell, and platen actuating means comprising hydraulic

rams, and a crosshead structure connected on said rams and pivotally connected directly to both platens, said rams swinging the hinged rods and sliding the platens outward on said rods as the flat faces of the platens apply pressure of sufficient magnitude to the cylindrical shell to form an arched top within the recess in the die and flatten the portions of the shell engaged by said flat faces.

5 7. In an apparatus for converting substantially cylindrical shells into culverts having substantially flat bottoms and arched tops, a die recessed in conformity with the desired arched top and adapted to receive a shell to be shaped, a pair of platens having substantially flat faces and disposed for engaging the shell at circumferentially spaced localities outside the die, said platens being adapted for initial engagement with the shell when the faces of the platens lie at an angle of substantially less than 130° to each other, means mounting the platens to rock about axes extending longitudinally relative to the shell, and means for moving the platens toward the die to flatten the shell where the platens engage it and to 10 shape its other side against the die recess, said last-mentioned means including means for rocking the platens in a direction to enlarge the aforesaid angle between their faces as they move against the shell and toward the die.

20 8. The apparatus of claim 3 which includes removable means associated with the lower platen, to permit operation on blanks having different diameters, and means intermediate the supporting structure and the rods for effecting vertical 25 adjustment of the hinge axes of the rods whereby the localities of said hinge axes may be changed to accord with the diameter of the blank under treatment.
